HAIR CURLING IRON HEATER

John L. Tilghman, 311 Convent Ave., New York, N.Y.

Filed Oct. 1, 1959, Ser. No. 57,766

Term of patent 7 years

(Cl. D81—10)

FIG. 2.

I claim:
The ornamental design for a hair curling iron heater, substantially as shown.
